(57) **CLAIM**

The ornamental design of the snow guard, as shown and described.

DESCRIPTION

This snow guard is designed to prevent snow and ice from sliding off a roof.

FIG. 1 is a top view of the snow guard showing our new design;

FIG. 2 is a bottom view thereof;

FIG. 3 is a front view thereof;

FIG. 4 is a rear view thereof;

FIG. 5 is side view thereof;

FIG. 6 is a section view thereof;

FIG. 7 is a rear perspective view thereof;

FIG. 8 is a front perspective view thereof; and,

FIG. 9 is a bottom perspective view thereof.
